DUAL RADIO DIRECTION FINDER

William P. Lear, North Hollywood, Calif., assignor, by mesne assignments, to Lear, Incorporated, Grand Rapids, Mich., a corporation of Illinois

Original application November 27, 1939, Serial No. 306,315, now Patent No. 2,379,363, dated June 26, 1945. Divided and this application September 27, 1943, Serial No. 503,870

9 Claims. (Cl. 250—11)

1

This invention relates to radio guidance receiver systems for mobile craft and more particularly to a novel radio instrument approach system and method for guiding an aircraft to a landing runway, a marine vessel into a slip, and the like. This case is a division of my copending application Serial No. 306,315, filed November 27, 1939, now Patent No. 2,379,363, issued June 26, 1945.

The receiver system of my present invention continuously indicates to a pilot his relative lateral position with respect to his destination. As described in my said copending application, two spaced non-directional transmitters are placed in line with the desired runway. The receiver system is simultaneously tuned to both transmitters and has two needle indicators arranged to continuously and independently point out the direction to each of the transmitters. The pilot is thus continuously made aware of his position with respect thereto.

In the present invention, two radio frequency tuning units are provided and are permanently connected to a single intermediate, audio, and control frequency amplifier circuit. The two ground stations are modulated with different predetermined audio frequency signals or tones. The modulated radio frequency waves are received by the corresponding tuning units. Means are provided for segregating the signal components due to the radio frequency waves and their associated modulations to effect resultant control signals and proper control actions on the associated rotatable antennae and respective indicators. The directional indications by the system are continuously operative and continuously effect accurate lateral guidance indications.

It is accordingly among the objects of this invention to provide a novel method of and means for radio approach guidance of mobile craft to a predetermined line of destination; to provide a novel lateral position radio indication method and system comprising two separate directional indicators; to provide a novel radio lateral position indicator system continuously effective in apprising the pilot of his exact relative position with respect to two spaced ground transmitter stations; to provide a novel radio guidance system employing a plurality of directional antennae and association radio frequency tuning units together with a common amplifier system and circuit means operative through a plurality of audio frequency signals for effecting continuous operation of the whole system.

These and further objects of the present inven-

2

tion will be apparent from the following description and the accompanying drawing. In the drawing, the single figure is a schematic block diagram of a continuously indicating receiver system responding to ground transmitter stations having separate carriers and control tone modulations.

According to the invention, separate loop antennae 10 and 10' are mounted upon individual shafts 11 and 11'. If desired, concentric mounting may be used. Two separate radio frequency tuning units 15 and 20 are used, and have individual non-directional antennae 12 and 13. Slip rings 14, 14' connect the winding of loop antennae 10 to leads 16 which are connected to the input of radio frequency tuning unit 15. Similarly, slip rings 14', 14' connect the winding of loop antenna 10' to leads 16' for connection to the input of radio frequency tuning unit 20. The position 20 of loop antenna 10 is controlled by reversible motor 17 connected to loop shaft 11 through electromagnetic clutch 18 and gearing 21, 22. Motor 17 is connected in parallel with magnetic clutch 18 and to leads 23 which, as will be described more 25 fully hereinafter, are connected to the control circuit. The motor system of rotatable loop antenna 10' comprises motor 17' connected to shaft 11' through electromagnetic clutch 18' and gearing 21', 22'. Motor 17' and clutch 18' are connected in parallel, through leads 23', to their control circuit. Tuning units 15 and 20 have separate manual tuning controls for tuning to the predetermined frequencies of the respective ground stations. Let us assume that unit 15 is 35 tuned to the "inner" transmitter station; and unit 20, to the "outer" transmitter station.

It is to be understood that suitable beat frequency oscillators are incorporated in the respective tuning units to give a signal output at the 40 predetermined intermediate frequency, such as 455 kilocycles. Intermediate frequency transformers 24 and 26 are connected respectively to the outputs of radio frequency tuning units 15 and 20. The secondary windings of intermediate 45 frequency transformers 24, 26 are electrically connected together by lead 27 to intermediate frequency transmission cable 28. Cable 28 is long, for remotely positioning the amplifier and control units of the remainder of the system from 50 tuning units 15, 20, preferably located in the cockpit adjacent the pilot, and is electrically shielded by ground shield 30.

The output of intermediate frequency transmission cable 28 is connected to the primary of 55 intermediate frequency transformer 31, the sec-

ondary of which is connected to the input of the intermediate frequency amplifier unit 32. Intermediate frequency amplifier 32 may well have several stages of amplification. The outputs of both radio frequency tuning units 15 and 20 are simultaneously amplified. A detector-audio frequency amplifier unit 33 is connected to the output of intermediate frequency amplifier 32. An aural unit 34 is connected to audio frequency amplifier unit 33 to provide audio signals for headphones 35, when desired. A power audio frequency amplifier 36 is connected to the output of amplifier unit 33 to sufficiently increase the level of the audio frequency components reaching it to actuate the loop control and relay units of the system.

In view of a single intermediate frequency amplifier 32 used for amplifying the outputs of two separate radio frequency tuning units 15, 20, I prefer to employ an automatic frequency control unit A. F. C., schematically indicated at 37. Automatic frequency control unit 37 is connected between radio frequency units 15 and 20 by respective leads 38 and 39. The design of the automatic frequency control circuit and its arrangement between units 15 and 20 is optional and in accordance with standard practice in the radio art. The resultant intermediate frequency of one of the tuning units, for example 15, may be used as the reference frequency initiating the automatic frequency control action of unit 37 to correspondingly control the resultant intermediate frequency of unit 20.

The automatic frequency control action is arranged so that a negligible or very small frequency difference exists between the intermediate frequency outputs of units 15 and 20. The automatic frequency control action is preferably performed directly on the beat frequency oscillator of unit 20 in order that the resultant intermediate frequency from the unit 20 may correspond closely with that of unit 15. The design of the A. F. C. unit 37 is preferably such that the difference frequency at the outputs of units 15 and 20 is of the order of 50 cycles or less to insure proper selective filtering action with respect to the audio frequency notes from the original carrier frequency waves.

In the illustrated system, two separate antenna control units 40, 45 are used. Control units 40, 45 are preferably of the type disclosed in my copending application, Serial Number 291,807, now Patent No. 2,379,362, issued June 26, 1945, and my Patent 2,308,521 employing two gaseous relay tubes or thyratrons, arranged for selectively operating reversible loop motors in accordance with received radio signals. The thyratron control circuits 40, 45 correspond to tube system 170 and motor control relays 172 illustrated in Fig. 5 of my said Patent No. 2,379,363. A preferred arrangement for the thyratron control circuit indicated schematically at 40, 45 together with a detailed consideration of its operation for loop position control is disclosed in my Patent No. 2,379,362 in connection with Figs. 11 and 12 thereof.

The thyratron control circuits 40, 45 are actuated by a locally generated audio frequency signal of 102.5 cycles, in the present case, emanating from generator 41. One portion of the thyratron control circuits 40, 45 is directly energized by the local 102.5 cycles signal, serving as a reference for phase and amplitude comparisons. Amplifier unit 42 is interposed between the thyratron control circuits 40, 45 and generator 41 to sufficiently

amplify the generated 102.5 cycles signal, and maintain the corresponding input to units 40, 45 at a predetermined level. The output of thyratron control circuit 40 is connected through leads 23 to the reversible loop motor 17 associated with loop antenna 10. Thyratron control circuit 45 is connected through leads 23' to reversible loop motor 17' of loop antenna 10'.

The 102.5 cycle generator unit 41 is also connected to each radio frequency tuning unit 15, 20, as schematically indicated by leads 43, 44, to properly modulate the received radio frequency signals with the 102.5 cycle note and derive the control signal for amplification and introduction to thyratron control circuits 40, 45 and effect selective motivation of the respective loop motors. Connection of generator 41 with tuning units 15, 20 is similar to the connection of the corresponding 102.5 cycle oscillator in the directional circuits of my Patent No. 2,308,521 specifically in connection with Fig. 2 thereof, and my Patent No. 2,379,362 specifically in connection with Fig. 9 thereof.

The illustrated localizer system is used with ground stations having different frequency carrier waves individually modulated by separate audio frequency notes. The audio frequency modulations on the received carrier waves are used to selectively operate the respective thyratron control circuits 40 or 45 to correspondingly continuously actuate loop antenna 10 or 10' and associated motor drive systems 17 and 17'. The frequency of each carrier wave is optional, as is the frequency of the audio frequency modulation thereon. The radio frequency waves as well as their audio frequency modulations are preferably non-harmonically related to avoid possible interfering action either in reception by the radio frequency tuning units 15, 20 or in the selective filtering action of the audio frequency control signals in the control circuits of the receiver, as will be understood by those skilled in the art.

In a preferred illustration of this invention the following conditions apply: The audio frequency modulation on the carrier wave (f_1) of the "inner" transmitter station is 900 cycles. The audio frequency modulation of the carrier wave (f_2) of the "outer" transmitter station is 3100 kilocycles. Carrier frequencies f_1 and f_2 are non-harmonically related. Their respective audio frequency modulations, 900 and 3100 cycles herein, which give corresponding side bands on their respective carrier waves, are non-harmonically related with respect to each other as well as with respect to the locally generated control signal, 102.5 cycles. It is to be understood that different audio frequencies may be chosen.

In the following analysis, any frequency difference between the intermediate frequency outputs of units 15 and 20 will be neglected, particularly in view of the automatic frequency control action by unit 37. Such residual beat note should not interfere with the action of the system. Should no automatic frequency control action be used, it is desirable to raise the frequency of the signal corresponding to the 102.5 cycle note so as to insure the selective filtering action on the 900 and 3100 cycle notes to be described.

Assuming no signal modulations on the radio frequency waves as received other than the 900 and 3100 cycle notes, the following relations hold: The component frequency waves received from the "inner" station by radio frequency tuning

unit 15 are (f_1+900) , (f_1) , and (f_1-900) . The component frequency waves received by radio frequency tuning unit 20 from the "outer" station are (f_2+3100) , f_2 , and (f_2-3100) . In accordance with the operation of the directional system, the local audio frequency signal, 102.5 cycles in the present case, further modulates each of the received radio frequency components, superimposing 102.5 cycle sidebands on each of the received radio frequency components. The resultant radio frequency signals in tuning units 15, 20, after modulation by the 102.5 cycle signal are then as follows: In tuning unit 15 we have $(f_1+900 \pm 102.5)$, $(f_1-900 \pm 102.5)$, $(f_1 \pm 900)$, $(f_1 \pm 102.5)$, and (f_1) . In radio frequency tuning unit 20 we have $(f_2 \pm 3100 \pm 102.5)$,

$(f_2-3100 \pm 102.5)$, $(f_2 \pm 3100)$, $(f_2 \pm 102.5)$

and (f_2) .

The locally modulated radio frequency components are then modified by respective beat frequency oscillators of the radio frequency units 15, 20 producing a common intermediate frequency output for both of the units. The intermediate frequency used is optional, and may for example be 455 kilocycles. The resultant intermediate frequency signal band comprises a plurality of frequencies each corresponding to a component of the modulated radio frequency signal band. Designating the intermediate frequency signal as (I. F.), we find the following component frequencies at the combined output of units 15, 20 as transmitted by cable 28 to the input of intermediate frequency amplifier 32: From unit 15 we obtain $(I. F.+900 \pm 102.5)$, $(I. F.-900 \pm 102.5)$, $(I. F. \pm 900)$, $(I. F. \pm 102.5)$, and $(I. F.)$. From unit 20 we obtain

$(I. F.+3100 \pm 102.5)$, $(I. F.-3100 \pm 102.5)$

$(I. F. \pm 3100)$, $(I. F. \pm 102.5)$, and $(I. F.)$.

The I. F. signal component band is amplified through intermediate frequency amplifier 32 and impressed upon detector-audio frequency amplifier unit 33. Rectification or demodulation of the intermediate frequency band results in the following audio frequency components, which are amplified by unit 33: Due to unit 15, we have (900 ± 102.5) , (900) , and (102.5) . Due to unit 20 we have (3100 ± 102.5) , (3100) , and (102.5) .

The respective audio frequency signals are thereupon amplified to a sufficiently high level by audio frequency power amplifier 36 for introduction to thyatron control circuits 40, 45 through selective band pass filter units 46, 47. Filter unit 46 is designed to efficiently pass the 900 cycle signal and its 102.5 cycle side bands, and reject the 3100 cycle signal with its 102.5 cycle side bands as well as reject the 102.5 cycle signal also present. The audio frequency signal components passing through the 900 cycle band pass filter 46 are accordingly: (900 ± 102.5) , and (900) .

Similarly, the 3100 cycle band pass filter unit 47 is designed to efficiently pass the 3100 cycle signal with its associated 102.5 cycle side band, and reject the 900 cycle signal with its side bands as well as the 102.5 cycle signal. Band pass filter 47 passes the audio frequency signals: (3100 ± 102.5) , and (3100) .

Band pass filters 46, 47 need not be bulky or expensive. The separation of the respective audio frequency signals and side bands is sufficiently wide so that these filters need not be very selective in their design. The band pass width of the filters is twice the local 102.5 cycle frequency,

or 205 cycles. The separation between the 900 cycle band and the 3100 cycle band is about 2000 cycles, which can be effected without much difficulty in the practical case. Similarly, the rejection of the 102.5 cycle signal by the 900 band pass filter is also readily effected in practice.

The output of 900 cycle band pass filter 46 is impressed upon rectifier unit 48 which demodulates the side bands to yield a 102.5 cycle resultant signal. The 102.5 cycle signal from rectifier 48 is directly impressed upon thyatron control circuit 49 for coaction therewith together with the reference 102.5 cycle signal impressed thereon through amplifier 42. The phase of the 102.5 signals from units 46 and 48 impressed upon thyatron control circuit 49 is initially adjusted to be either in phase or 180° out of phase relation by means similar to phase network 168 of Fig. 5 of my Patent No. 2,379,363.

It is feasible to include an audio frequency amplifier and 102.5 cycle pass filter in rectifier unit 48 to insure efficient actuation of control circuit 49. Control circuit 49 motivates motor 17 of loop 10. The 3100 cycle signal and its 102.5 cycle side bands pass from the output of filter unit 47 into rectifier unit 49 to yield a corresponding 102.5 cycle signal for impression upon thyatron control circuit 45 to control the operation of loop motor 17.

The 102.5 cycle signal derived from rectifier 48 and impressed upon control circuit 49 corresponds in magnitude and phase to that of the radio frequency signal as received by loop antenna 10 and impressed upon radio frequency tuning unit 15. Thyatron control circuit 49, in response to the control signal it receives from unit 48, operates loop motor 17 in a clockwise or counterclockwise direction to bring loop antenna 10 to a null signal position or bearing relationship with the "inner" transmitter. The output of rectifier 49 correspondingly controls the operation of thyatron control circuit 45 to properly orient loop motor 17 to continuously held loop antenna 10' in the null signal position or bearing relationship with the "outer" transmitter.

A composite indicator 50 with "in" and "out" needles 1 and 2 is coupled with loop antennae 10 and 10' to afford continuous directional indication and lateral guidance. A separate telemetering system is connected to shaft 11 of loop antenna 10 so that needle 1 of indicator 50 will accurately point out the position which loop antenna 10 is made to assume, being a bearing on the "in" transmitter station. Selsyn type transmitter 51 is used, energized by a suitable battery, and connected to indicator 50 through cable 52. Similarly, a separate telemetering system is connected to shaft 11' of loop antenna 10' so that needle 2 of indicator 50 will accurately point out the position which loop antenna 10' is made to assume, being a bearing on the "out" transmitter station. A Selsyn type transmitter 51' is used, energized by a suitable battery, and connected to indicator 50 through cable 52'. Indicator 50 contains two coaxially mounted receiver Selsyn units in connection with transmitters 51 and 51'.

Indicator 50 has a zero index 0 corresponding to the axis of the mobile craft. After tuning of the radio frequency units 15 and 20 to the carrier frequency of the transmitting stations, instrument approach guidance, as described in connection with Fig. 1 of my Patent No. 2,379,363, is effected. The arrangement is such as to continuously orient the respective antennae and

their associated needles on indicator 50 to point out, preferably to within 1° of arc, the direction toward the respective transmitter stations.

The system may be readily converted to a general automatic direction finder such as the system described in my Patent No. 2,308,521. Switch 55 may be used to by-pass the signal output of power audio frequency amplifier 36 directly to thyratron control circuits 40 through connection leads 56. With switch 55 in the open position illustrated, the system operates as a localizer in the manner described. Upon closing switch 55 to the "A. D. F." position, the system is connected to a general automatic direction finder using only antenna 10, its motor 17 and one of the thyratron control units therefor, 40 in the present case. General automatic direction finder operation does not entail a predetermined modulation of the transmitted carrier as in the localizer operation where 900 and 3100 cycle modulations are used. The control signal resulting from a generally received radio frequency signal, accordingly, would not suitably pass through filter units 43 and 47. The 102.5 cycle signal derived from the received radio frequency signal is introduced to thyratron control circuit 40 directly through leads 56 and switch 55, for actuating the circuit to operate the corresponding loop antenna 10 and its associated indicator 1 in accordance with the direction towards the station tuned-in by radio frequency tuning unit 15.

While one embodiment of the invention has been shown and described in detail to illustrate the application of the principles thereof, it will be obvious that the invention may be otherwise embodied without departing from such principles.

What is claimed is:

1. The method of guiding a mobile craft which comprises transmitting signals of different radio frequencies having individual predetermined tone modulations from a plurality of points; directionally receiving the different radio signals aboard the craft; impressing a predetermined control modulation on each of said received radio signals; transforming the different radio frequency signals to corresponding signals with substantially the same carrier wave frequency which contain the control and tone modulations; commonly amplifying the transformed signals and deriving their corresponding tone and control modulations; segregating the respective tone modulations including their respective control modulations; and obtaining therewith a directional bearing on each of the transmitted radio signals with respect to the position of the mobile craft.

2. The method of guiding a mobile craft with respect to a predetermined path which comprises transmitting signals of different radio frequencies having individual predetermined tone modulations from a plurality of points; directionally receiving the different radio signals aboard the craft; impressing a predetermined control modulation on each of the directionally received radio signals; transforming the different radio frequency signals to corresponding signals of a substantially common carrier frequency which separately contain the original tone and control modulations; commonly amplifying the transformed signals and deriving their corresponding bands of tone and control modulations; segregating the respective bands of tone modulations including their respective control modulations; and respectively obtaining therewith a directional bearing on each of the transmitted radio signals

with respect to the position of the mobile craft.

3. The method of guiding a mobile craft with respect to a predetermined path which comprises transmitting signals of different radio frequencies having individual predetermined tone modulations from a plurality of points; directionally receiving the different radio signals simultaneously aboard the craft; impressing a predetermined control modulation on each of the directionally received radio signals; transforming the different radio frequency signals to corresponding signals of a substantially common intermediate frequency which separately contain the original tone and control modulations; jointly amplifying the transformed signals and deriving their corresponding bands of modulations; segregating the respective bands of tone modulations including their respective control modulations; suppressing the original predetermined tone modulations from the bands; and respectively obtaining with the respective control modulations a directional bearing on each of the transmitted radio signals with respect to the position of the mobile craft.

4. The method of guiding a mobile craft with respect to a predetermined path which comprises transmitting signals of different radio frequencies having individual predetermined tone modulations from a plurality of points; directionally receiving the different radio signals simultaneously aboard the craft; generating a predetermined control signal aboard the craft; impressing such generated control signal on each of the directionally received radio signals; transforming the different radio frequency signals to corresponding signals with a substantially common intermediate frequency which separately contain the original tone and control signal modulations; jointly amplifying the transformed signals and deriving their corresponding bands of tone modulation; segregating the respective tone modulations; suppressing the original predetermined tone modulations from the bands; individually comparing the resulting control signals with the generated signals; and deriving therefrom a directional bearing on each of the transmitted radio signals with respect to the position of the mobile craft.

5. A directional radio receiving system comprising a plurality of rotatable directional antennae having individual motive drives; a radio frequency tuning unit connected to the winding of each of said antennae for tuning in individual received tone-modulated radio frequency signals; a signal source connected to each tuning unit for modulating the tuned-in signals with a control tone; means associated with said tuning units for transforming the radio frequency signals to corresponding signals having substantially the same frequency; means including circuit connections with said tuning units for amplifying said transformed signals and deriving their original and control tone modulation signals; filter means for segregating the derived signals; and control means responsive to said segregated signals for individually operating said motive drives to orientate their associated loop antennae into directional bearing relationship with the respective radio signals.

6. A radio guidance receiving system comprising two rotatable directional antennae having individual motive drives; a radio frequency tuning unit connected to the winding of each of said antennae for tuning in individual tone-modulated radio frequency signals; a local audio frequency signal source connected to each of said

tuning units for modulating the tuned-in radio frequency signals with a control tone; means associated with said tuning units for transforming the radio frequency signals to corresponding signals having substantially the same intermediate frequency including circuit connections with said tuning units for amplifying said intermediate frequency signals and deriving their original and control tone modulation signals; filter means for segregating bands of the such derived signals; and control means responsive to said segregated bands for individually operating said motive drives to orientate their associated loop antennae into directional bearing relationship with the respective radio signals.

7. A radio guidance receiving system comprising two rotatable directional antennae having individual motive drives; a radio frequency tuning unit connected to the winding of each of said antennae for tuning in individual tone-modulated radio frequency signals; a local audio frequency signal source connected to each of said tuning units for modulating the tuned-in radio frequency signals with a control tone; means associated with said tuning units for transforming the radio frequency signals to corresponding signals having substantially the same intermediate frequency including an automatic frequency control component in circuit therewith; means including circuit connections with said tuning units for jointly amplifying said intermediate frequency signals and deriving their original and control tone modulation signals; filter means for segregating bands of such derived signals and for suppressing said original tone modulations; control means responsive to said segregated bands for individually operating said motor drives to orientate their associated loop antennae into directional bearing relationship with the respective radio signals; and an indicator coupled with each of said rotatable antennae to indicate their bearing positions.

8. A radio guidance receiving system comprising two rotatable directional antennae having individual motive drives; a radio frequency tuning unit connected to the winding of each of said antennae for tuning in individual tone-modulated radio frequency signals; a local audio frequency signal source connected to each of said tuning units for modulating the tuned-in radio frequency signals with a control tone; means associated with said tuning units for transforming the radio frequency signals to corresponding signals having substantially the same intermediate frequency including an automatic frequency control component in circuit therewith; means including circuit connections with said tuning units for jointly amplifying said intermediate fre-

quency signals and deriving their original and control tone modulation signals; filter means for segregating bands of such derived signals; rectifying means for suppressing the original tone modulations; and control circuit means connected to said local signal source for comparing the resulting control tone modulations with the control tone from said source and individually operating said motor drives to orientate their associated loop antennae into directional bearing relationship with the respective radio signals.

9. A radio guidance receiving system comprising two rotatable directional antennae having individual reversible motor drives; a radio frequency tuning unit connected to the winding of each of said antennae for tuning in individual tone-modulated radio frequency signals; a local audio frequency signal source connected to each of said tuning units for modulating the tuned-in radio frequency signals with a control tone; means associated with said tuning units for transforming the radio frequency signals to corresponding signals having substantially the same intermediate frequency; means including circuit connections with said tuning units for jointly amplifying said intermediate frequency signals and deriving their original and control tone modulation signals; filter means for segregating bands of the derived signals; separate control means responsive to said segregated bands for individually operating said motor drives to orientate their associated loop antennae into directional bearing relationship with the respective radio signals; an indicator coupled with each of said rotatable antennae to indicate their bearing positions; and selectively operable switch means for connecting such amplifying and tone modulation deriving means directly to said control means to condition said radio receiving system for operation as an automatic direction finder with respect to one of said radio frequency signals.
